UNITED STATES PATENT OFFICE.

FRED JOHN SHANISEY, SR., OF ROCHESTER, NEW YORK, ASSIGNOR TO FITZ-EMPIRE DOUBLE PIVOT LAST COMPANY, OF AUBURN, MAINE, A CORPORATION OF MAINE.

COLLAPSIBLE LAST.

Application filed June 24, 1921. Serial No. 480,049.

To all whom it may concern:

Known I, FRED J. SHANISEY, Sr., a citizen of the United States, residing at Rochester, in the county of Monroe and State of New York, have invented certain Improvements in Collapsible Lasts, of which the following description, in connection with the accompanying drawings, is a specification, like reference characters on the drawings indicating like parts in the several figures.

This invention relates to collapsible lasts and is herein shown and described in connection with a preferred form of hinge last. Hinged lasts have come to be regarded as desirable in many types of shoe making because of their rapid and positive shortening effect which permits easy removal of the last from the shoe or insertion therein. Collapsible lasts are generally held in operative lengthened position by so-called locking mechanisms of the positive or impositive types. The former, which does not collapse under pressure, is regarded as the better for many kinds of work, and it is with it that the present invention has to deal. Difficulty has been experienced with the positive lock in that when disengaged to permit the collapse of the last, it was necessary for the operator to hold the locking member out of operative position until a portion at least of the collapsing movement had been effected, a condition which militated against convenience in operation as some special tool was necessary to hold the locking member out of operative position while the collapse was begun, or else the operator's fingers were liable to be injured by being squeezed between the last parts while holding the locking member out of operative position. A second objection to the use of such locking members has been that when the last was extended again after collapse, some special manipulation was necessary in order to restore the member to operative position.

Accordingly it is an object of the present invention to provide a novel positive locking device for a hinged last which shall avoid these and other objections. An important feature of the invention consists in a novel locking device organized so that, automatically, when the locking member is displaced from operative position, it will be

positively held in inoperative position, being preferably released therefrom by the collapsing movement of the last. In the last shown, this is accomplished by providing a fixed point in a last part, economically chosen as a part of the bonding mechanism, over which the locking member hooks or latches automatically as it is displaced from operative position and from which it is unhooked as the last is collapsed, thereby being able to return to operative position automatically when the last is extended again.

These and other features of the invention will be better understood from the following description of a preferred embodiment thereof selected for illustrative purposes and shown in the drawing in which

Fig. 1 is a broken away view of the hinge and locking mechanism of the last in extended position.

Fig. 2 shows the condition of the parts after the moving of the locking member from operative position.

Fig. 3 shows the parts after collapse of the last.

The illustrated last comprises a forepart 10 and a heel part 12 having a thimble hole 14 and separated by a cut of any desired form permitting hinge movement of one part on the other. In the last shown the cut comprises a circular knuckle 16 on one last part extending into a correspondingly shaped depression in the other, the knuckle being joined to the lower surface of the last by a straight cut 18 as is well known, and the last parts being separated at the upper part of the last by a V-shaped opening 20 permitting the collapse of the last by relative movement of the parts around the center of the knuckle.

The two last parts may be bonded in any convenient manner, a very simple bonding device being shown in the drawing. This consists conveniently of two identical plates 24 and 26 anchored in that one of the last parts not containing the knuckle by pins 28, 30. Between these plates, pivotally mounted on the pin 28, is a locking member 32. The pintle 22 passes through the plates and through the center of the knuckle 16 in the other last part, thus, in combination with the plates and the pins 28, 30, bonding

the two last parts together for hinge movement about the pintle 22. Another plate or plates corresponding to 24 and 26 may be anchored in the heel part and bored to 5 accommodate the pintle 22, thus strengthening the joint if desired. The plates take the tensile stress required to hold the last parts together, and their pivotal mounting at 22 permits the collapse of the last.

10 The locking member which, as has been stated, is pivoted on the pin 28 in one last part has a shoulder 32' which normally contacts with a pin 34 mounted in the other last part. The shoulder 32' preferably 15 makes an angle with the line joining the pins 28 and 34 so that it can wedge into contact with the pin 34 and take up any wear between the last parts. The locking member is shown as slotted at 36 and comprises in the slot a plunger 38 arranged for 20 sliding movement. A spring 40 presses the plunger outwardly. The locking member, plunger and spring are mounted between the plates 24 and 26 so that the parts are conveniently held against displacement. Means, 25 preferably an abutment in the last, is provided for holding the locking member in inoperative position. Conveniently a portion of the bonding mechanism is utilized 30 for this purpose, as will be seen, thus economizing parts and operations in the last construction. The lower part of the plunger is formed with the cam surface 42 which is of wedge shape and forms two notches 43 35 and 45 with the sides of the slot 36, which are preferably lengthened for that purpose, and also to effect efficient guiding action on the plunger. The plunger normally engages in the notch 43 a part of the bonding mechanism, (the abutment above mentioned) 40 shown as the pin 30 on one side of the angle of its wedge and tends, under the pressure of the spring 40, to wedge the locking member up against the pin 34 as shown in Fig. 45 1. When the locking member is depressed by pressing on its handle 44, which projects into the opening 20 for convenient direct normal operation, see Fig. 2, it rotates about the pin 28, thereby carrying the plunger 38 over to the other side of the pin 30 so that 50 the other notch 45 at the other side of the cam 42 rests on the pin 30. This position is shown in Fig. 2 and it will be plain that pressure of the spring in this position of 55 the parts causes a reaction between the plunger and the pin 30 which tends to retain resiliently the locking member 32 in inoperative position as shown in said Fig. 2. The movement of the locking member to inoperative position may be arrested at any 60 convenient point in various ways as by contact of the handle 44 with the pin 34 or by contact of the lower portion of the locking member with the pin 30 both of which arrangements are shown in Fig. 2. The cam

42 could alone hold the locking member in its two positions, but the notch construction makes the action more positive and reliable.

It will be noticed in Fig. 2 that that portion of the cam surface 42 which is in contact with the pin 30 makes a slight angle with the line joining the pins 28 and 30 which assists the friction of the parts in effecting the holding of the locking member in inoperative position. The locking member, through its plunger 38, is in effect hooked or latched over the pin 30 when in inoperative position and will thereby be held in such position indefinitely without the interposition of tools or the operator's fingers to effect this result.

The last is collapsed by a movement of rotation of the heel part relatively to the forepart about the pin 22, as shown in Fig. 3. This movement, through pressure between the pin 34 and the locking member, these parts being relatively arranged for this purpose, rotates the locking member counterclockwise around the pin 28 so that the projection of the cam 42 rides back over the pin 30, and the other side of the cam comes into contact with the pin. This is shown in Fig. 3. The spring 40 now tends to throw the locking member up into operative position and when the heel part is brought back into extended position, the locking member will rise as soon as the pin 34 passes the corner of the shoulder 32', and the shoulder and pin will be brought firmly into contact again, as shown in Fig. 1. The locking member, therefore, when thrown out of operative position is automatically held in inoperative position and is restored to operativeness by the collapsing movement of the last.

Having described my invention, what I claim as new and desire to secure by Letters Patent of the United States is:—

1. A collapsible last comprising a heel part and forepart arranged for relative movement to collapse the last, a locking member engaging said parts to prevent such collapsing movement and hold the parts in extended position, said locking member being movable from operative position to permit the collapse of the last and being accessible for effecting such movement by the operator's fingers, and means for automatically catching and holding said locking member in inoperative position when so displaced, constructed and arranged to release it for locking operation again upon the collapsing movement of the last.

2. A last comprising a heel part and forepart hinged together for relative collapsing movement, a strut-like locking member extending from one of said last parts to the other to prevent such collapsing movement, said locking member being movable from operative position to permit collapse of the

last, an abutment fixed in one last part, said locking member being constructed and arranged to engage said abutment when moved from operative position in such manner as to be held against return to said operative position, and a second abutment in a last part constructed and arranged to contact with said locking member when the last is collapsed and to move it out of operative relation to said first-named abutment.

3. A last comprising a forepart and heel part hinged together for relative collapsing movement, a strut-like locking member pivoted in one of said last parts and abutting the other to prevent collapsing movement, said locking member having a notch, an abutment fixedly mounted in the last part in which the locking member is hinged constructed and arranged to enter said notch when the locking member is moved from operative position to hold said locking member in inoperative position, and a second abutment mounted in said last part in which said locking member is not pivoted, constructed and arranged to disengage the notch from the first-named abutment as the last is collapsed, thereby permitting the locking member to return to operative position when the last is extended.

4. A last comprising a forepart and heel part divided by a cut providing a V-shaped opening at the top and hinged together for relative collapsing movement, and a locking member pivoted in one last part and engaging the other, and projecting into said V-shaped opening for convenient manual operation, said locking member being movable to inoperative position to permit collapse of the last, an abutment member mounted in a said last part, one of said abutment and locking members having a notch with which the other is arranged to co-operate when the locking member is moved from operative position to hold the locking member in inoperative position, and means for disengaging the notch and its co-operating member as the last is collapsed, whereby the locking member may be returned to operative position.

5. A last comprising a forepart and heel part divided by a cut providing a V-shaped opening at the top and hinged together for relative collapsing movement, and a locking member pivoted in one last part and engaging the other, and projecting into said V-shaped opening for convenient manual operation, said locking member being movable to inoperative position to permit collapse of the last, and an abutment member mounted in a said last part, one of said abutment and locking members having a notch with which the other is arranged to co-operate when the locking member is moved from operative position to hold the locking member in inoperative position, the

last parts and the abutment and locking members being constructed and arranged to effect disengagement of the two said members by virtue of the collapsing movement of the two said last parts.

6. A last comprising a forepart and heel part divided by a cut providing a V-shaped opening at the top and hinged together for relative collapsing movement, and a locking member pivoted in one last part and engaging the other, and projecting into said V-shaped opening for convenient manual operation, said locking member being movable to inoperative position to permit collapse of the last, an abutment member mounted in said last, one of said abutment and locking members having a projecting angle with the sides of which the other member is arranged to co-operate in turn to hold the locking member in operative and inoperative position respectively, the projecting angle being arranged relatively to pass over its co-operating member when the locking member is moved from operative position, whereby the locking member is held in inoperative position prior to the initial collapsing movement, and means for again relatively moving the angle over its co-operating member as the last is collapsed, whereby the locking member is permitted to pass to operative position as the last is again extended.

7. A last comprising a forepart and heel part divided by a cut providing a V-shaped opening at the top and hinged together for relative collapsing movement, and a locking member pivoted in one last part and engaging the other, and projecting into said V-shaped opening for convenient manual operation, said locking member being movable to inoperative position to permit collapse of the last, an abutment member mounted in said last, one of said abutment and locking members having a projecting angle with which the other member is arranged to co-operate to hold the locking member in inoperative position, the projecting angle being arranged relatively to pass over its co-operating member when the locking member is moved from operative position, whereby the locking member is held in inoperative position prior to the initial collapsing movement, and means for again relatively moving the angle over its co-operating member as the last is collapsed, whereby the locking member is permitted to pass to operative position as the last is again extended.

8. A last comprising a forepart and a heel part, bonding mechanism for uniting said parts comprising a member which takes stress requisite for holding said parts together and arranged to permit collapsing movement of said parts, and a locking member pivoted in one last part and abutting the other to prevent the said collapsing move-

ment, the said stress taking member being arranged to co-operate with the locking member on movement of the latter from locking position to hold it in inoperative position and permit collapse of the last.

9. A last comprising a forepart and a heel part, bonding mechanism for uniting said parts for collapsing movement, and a locking member pivoted in one last part and abutting the other to prevent the said collapsing movement, a portion of the bonding mechanism being arranged to co-operate with the locking member when the latter is moved from locking position to hold it in inoperative position and permit collapse of the last, said co-operation being broken by relative movement between the last parts during collapse whereby the locking member is again rendered operative.

10. A last comprising a forepart and a heel part, bonding mechanism for uniting said parts for collapsing movement, a locking member pivoted in one last part and abutting the other to prevent the said collapsing movement, a portion of the bonding mechanism being arranged to co-operate with the locking member when the latter is moved from locking position to hold it in inoperative position and permit collapse of the last, and means acting to break said co-operation on relative movement of the last parts during collapse whereby the locking member is again rendered operative.

11. A collapsible last having a heel part and a forepart arranged for relative collapsing movement, a locking member arranged for direct manual operation to brace said parts against such movement, a spring for resiliently holding said locking member in operative position and arranged also to hold said locking member in inoperative position when moved thereto, and means for overcoming the action of the spring in the inoperative position of the locking member as the last collapses.

12. A collapsible last having a heel part and a forepart arranged for relative collapsing movement to shorten the last, a locking member mounted in one said last part and engaging the other to prevent said collapsing movement, an abutment fixed in a last part arranged to engage and hold the locking member in inoperative position when it is displaced from operative position, and means mounted in the last for movement relatively to the locking member as the last collapses, constructed and arranged to disengage the locking member from the abutment whereby the locking member is permitted to return to operative position.

13. A last comprising a forepart and heel part divided by a cut providing a V-shaped opening at the top and hinged together for relative collapsing movement, and a lock-

ing member pivoted in one last part and engaging the other, and projecting into said V-shaped opening for convenient manual operation, said locking member being movable to inoperative position to permit collapse of the last, an abutment member mounted in a said last part, one of said abutment and locking members having a shoulder relatively over which the other is arranged to move as the locking member is moved from operative position, whereby the locking member is held in inoperative position, and means for forcing the other member and the shoulder relatively over each other in the reverse sense as the last is collapsed, whereby the locking member may be returned to operative position.

14. A last comprising two last parts movably connected together, a detent movably mounted on one of said last parts and abutting on the other of said last parts to hold the last in an expanded condition, means for positively locking the detent out of co-operation with said other last part, and means for effecting the release of said detent on the collapsing of the last to permit the cooperation of the detent with said other last part upon the expansion of the last.

15. A last comprising two last parts movably connected together, a detent movable on one of said last parts and adapted to cooperate with the other to hold the last in an expanded position, means for holding the detent out of cooperative relation with the last part with which it cooperates, and means operable upon the collapsing of the last for releasing said detent to permit the latter to cooperate again with the last part upon the expansion of the last.

16. A last comprising two movably connected last parts, a locking detent for holding the last in an expanded condition, a spring acting on said detent to hold it in said holding position, and means for causing the said spring action to cease holding said detent in said holding position when the lock is moved to unlocking position and automatically to bring said spring into action when the last parts are shifted relatively to each other for the collapsing of the last.

17. A last comprising a pair of movably connected last parts, a locking detent for holding the last in an expanded condition, mounted on one of said last parts, a spring for acting on said detent to hold it in said holding position, and means on the other of said last parts for causing the action of the spring on the detent to cease holding it in said holding position when the detent is moved to unlocking position and automatically to bring said spring into action when the last is collapsed.

18. A collapsible last comprising two last parts, a bonding mechanism connecting said

last parts together comprising a member transmitting stress from one last part to the other to hold them together, an abutment on one of the said last parts, a detent mounted on the other of said last parts, and cooperating portions integral with the said detent and stress-transmitting member respectively for holding the detent out of locking relation with the abutment while the last is in an expanded condition.

19. A last comprising two movably connected last parts, a locking detent for hold-

ing said last in an expanded condition, a spring acting on said detent and having a pressure position and a locking position 15 to which it is shifted when the detent is moved away from its detaining position, to hold such detent away from such detaining position, and means cooperating with the detent on the collapsing of the last to shift 20 the spring to pressure position.

In testimony whereof I have signed my name to this specification.

FRED JOHN SHANISEY, Sr.
